DRAPE CURTAIN

Charles C. Friedberg, New York, N. Y., assignor,
by mesne assignments, to Trio Curtain Co.,
New York, N. Y.

Application June 24, 1942, Serial No. 448,244

6 Claims. (Cl. 160—330)

This invention relates to new and useful improvements in a drape curtain.

More specifically, the invention proposes the formation of a drape curtain having an equilateral triangularly shaped central top piece and right angle triangularly shaped side pieces connected to the sides of the top piece so that when the drape curtain is hung from a curtain rod the altitude of the side pieces will be vertical in a manner to cause the top piece to be ruffled.

Another object of this invention proposes forming the drape curtain with a hem forming a passage through which a curtain rod is adapted to be extended in a manner to permit the drape curtain to be hung from a curtain rod as hereinbefore referred to.

It is a further object of this invention to form the top piece of the curtain with an alternate passage through which the curtain rod is adapted to be passed in a manner to change the appearance of the drape curtain when hung from the rod.

A still further object of this invention proposes forming a drape curtain which is simple and durable and which will produce an unusual effect when hung from a curtain rod and which may be manufactured and sold at a reasonable cost.

For further comprehension of this invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a view of a drape curtain constructed in accordance with this invention and hung from a curtain rod.

Fig. 2 is a developed view of the drape curtain.

Fig. 3 is a partial vertical sectional view taken on the line 3—3 of Fig. 2.

Fig. 4 is a view similar to a portion of Fig. 2, but illustrating a modification of the invention.

Fig. 5 is a vertical sectional view on the line 5—5 of Fig. 4.

The drape curtain, according to this invention, comprises an equilateral triangularly shaped central top piece 10 having its bottom corners cut off along a line 11. This line 11 extends at right angles to the sides of the top piece 10. A rounded base 12 is formed on the top piece between the ends of the cut off corners.

Right angle triangularly shaped side pieces 13 are located on either side of the top piece 10 and

have their acute base corners cut off along the lines 14. The cut off corners of the top piece 10 and the side pieces 13 are secured together by lines of stitches 15 to form a unit of the top piece 10 and the side pieces 13.

Hems are extended along the bases of the side pieces 13 and the sides of the top central piece 10. These hems are formed by bending in the edges of the top central piece 10 and the side pieces 13 and securing these bent in portions in position by lines of stitches 16 forming a passage way 17 for a curtain rod 18. When the drape curtain is hung from the curtain rod 18 as shown in Fig. 1 the altitudes of the side pieces become vertical and the top central piece becomes draped.

The side pieces 13, adjacent to the hemmed edges are folded at 13a to produce a finished side edge for the curtain.

In Figs. 4 and 5 the top central piece 10 is formed with an auxiliary passage 19 extending horizontally between the sides of the top central piece. This passage 19 is connected at its ends with the passage 17. The passage 19 is formed by attaching a piece of cloth material 20 to the back face of the top central piece 10 by lines of stitches 21. When engaging the curtain rod 18 through the passage 17, it may be completely engaged through this passage or may be diverted through the auxiliary passage 19 to vary the draped effect of the top central portion 10 when hung from the rod 18.

In other respects this form of the invention is similar to the previous form and like reference numerals are used to identify like parts in each of the several views.

It is to be understood that by means of this arrangement, a drape curtain is created which requires only a single curtain rod for hanging. By simply sliding the curtain on this rod the drapes are automatically formed.

While I have illustrated and described the preferred embodiments of my invention, it is to be understood that I do not limit myself to the precise constructions herein disclosed and the right is reserved to all changes and modifications coming within the scope of the invention as defined in the appended claims.

Having described my invention, what I claim as new and desire to secure by United States Letters Patent is:

1. A drape curtain, comprising an equilateral triangularly shaped central top piece having its bottom corners cut off, right angle triangularly shaped side pieces having their acute base corners cut off and attached at the cut lines to the

respective sides of said top piece resulting from the removal of the corners thereof and having their bases continuing from the sides of said central top piece, and hems extended along the bases of said side pieces and the sides of said top central piece forming a passageway for a curtain rod, whereby when said drape curtain is engaged on a curtain rod the sides of said side pieces will be perpendicular to the bases and said central top piece will be draped.

2. A drape curtain, comprising an equilateral triangularly shaped central top piece having its bottom corners cut off, right angle triangularly shaped side pieces having their acute base corners cut off and attached at the cut lines to the respective sides of said top piece resulting from the removal of the corners thereof and having their bases continuing from the sides of said central top piece, and hems extended along the bases of said side pieces and the sides of said top central piece forming a passageway for a curtain rod, whereby when said drape curtain is engaged on a curtain rod the sides of said side pieces will be perpendicular to the bases and said central top piece will be draped, said central top piece having its bottom rounded between said cut off corners.

3. A drape curtain, comprising an equilateral triangularly shaped central top piece having its bottom corners cut off at right angles to the non-common sides, right angle triangularly shaped side pieces having their acute base corners cut off and attached at the cut lines to the respective sides of said top piece resulting from the removal of the corners thereof and their bases continuing from the sides of said central top piece, and hems extended along the bases of said side pieces and the sides of said top central piece forming a passageway for a curtain rod the sides of said side pieces will be perpendicular to the bases and said central top piece will be draped.

4. A drape curtain, comprising an equilateral triangularly shaped central top piece having its bottom corners cut off, right angle triangularly shaped side pieces having their acute base cor-

ners cut off at right angles to said bases and attached at the cut lines to the respective sides of said top piece resulting from the removal of the corners thereof and having their bases continuing from the sides of said central top piece, and hems extended along the bases of said side pieces and the sides of said top central piece forming a passageway for a curtain rod, whereby when said drape curtain is engaged on a curtain rod the sides of said side pieces will be perpendicular to the bases and said central top piece will be draped.

5. A drape curtain, comprising an equilateral triangularly shaped central top piece having its bottom corners cut off, right angle triangularly shaped side pieces having their acute base corners cut off and attached at the cut lines to the respective sides of said top piece resulting from the removal of the corners thereof and having their bases continuing from the sides of said central top piece, and hems extended along the bases of said side pieces and along the sides and below the apex of said top central piece forming a passageway for a curtain rod, whereby when said drape curtain is engaged on a curtain rod the sides of said side pieces will be perpendicular to the bases and said central top piece will be draped.

6. A drape curtain, comprising an equilateral triangularly shaped central top piece having its bottom corners cut off, right angle triangularly shaped side pieces having their acute base corners cut off and attached at the cut lines to the respective sides of said top piece resulting from the removal of the corners thereof and having their bases continuing from the sides of said central top piece, and hems extended along the bases of said side pieces and along the sides and below the apex of said top central piece forming a passageway for a curtain rod, whereby when said drape curtain is engaged on a curtain rod the sides of said side pieces will be perpendicular to the bases, said central top piece will be draped, said passageway below the apex being formed by attaching a piece of cloth material across the back face of said top central piece.

CHARLES C. FRIEDBERG.
